(57) **CLAIM**

The ornamental design for the charging case with wireless earphones, as shown and described.

DESCRIPTION

FIG. 1 is a front perspective view of a charging case with wireless earphones showing my new design, with the charging case in an open position;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an exploded view of the charging case with wireless earphones, with the charging case in an open position thereof.

The broken lines in the drawings illustrate the portions of the charging case with wireless earphones, which form no part of the claimed design.
